HARRY P. STEVENS AND WINTHROP S. HORTON, OF NEW YORK, N. Y.

AUTOMATIC CLUTCH.

Application filed November 8, 1924. Serial No. 748,638.

To all whom it may concern:

Be it known that we, HARRY P. STEVENS and WINTHROP S. HORTON, citizens of the United States, each residing in the borough 5 of Manhattan, city, county, and State of New York, have invented certain new and useful Improvements in Automatic Clutches, of which the following is a full, clear, concise, and exact description.

10 Our invention relates particularly to clutch devices in which a driven member is controlled by a driving member, in such a manner that when the driving member is moved or rotated in one direction or in either 15 of two directions, the parts will be locked together, while on the other hand when there is no driving motion transmitted from the driving part to the driven part, the respective parts will be held firmly in their relative 20 positions.

Our invention is particularly adapted for use with window raising and lowering devices of the type used on closed automobile bodies, wherein the windows are usually operated by rotating a crank within the car.

In such devices it is very important that the windows may be raised and lowered freely and easily and, at the same time, when it is desired to leave the windows in 30 any position, either fully open or closed, or partly open, the operating parts will be held firmly in position and will not be displaced by the motion of the car passing over rough portions of the road.

35 For a detailed description of the various modifications of our improved automatic clutch, reference may be had to the following specification and the accompanying drawings forming a part thereof, in which—

40 Fig. 1 is a side elevation, partly in section, of a simple form of our device illustrating the main principle thereof;

Fig. 2 is a similar view of another form, partly in section, in which the connection 45 between the driving and driven members is brought about in either of two rotary directions;

Fig. 3 is a transverse sectional view on the line 3—3 of Fig. 2;

50 Fig. 4 is an elevational view of another form of our device particularly shown partly in section and adapted for application to means for raising and lowering windows in automobile bodies above referred to.

55 Fig. 5 is a transverse sectional view taken substantially on the line 5—5 of Fig. 4; and

Fig. 6 is an elevational view showing the connections necessary for adapting our improved clutch to a window raising and lowering device of the usual type, the front 60 part of the casing being removed.

Referring to Fig. 1 of the drawings the numeral 1 indicates a shaft or driving member, to which is rigidly fastened by a set screw 2, or any suitable means, a disc 3 carrying a collar 4. The collar 4 carries a radially projecting arm 5 adapted to engage a stop 6 extending laterally from an annular member 7 which fits rotatively about the disc 3 and fits accurately but also rotatively 65 within the driven member 8, which is annular as indicated and may constitute a gear as indicated by the teeth 9, or may be a fixed or stationary member as indicated at 10, if it be desired to allow the shaft 1 to rotate in one direction only.

It will be noted that the disc 3 is eccentrically located within the annular member 7 but that the axis of the shaft 1 is concentric with the axis of the driven member 8.

80 The operation of this device is as follows: Assuming that the shaft 1 and the disc 3 are being rotated in the direction of the arrows in Fig. 1, the arm 5 will bear against the stop 6. This will cause shaft 1, the disc 3 and the annulus 7 to rotate together within the annular gear 8, and there will be no interconnection between the driven shaft and the gear 8, or the fixed ring 10.

On the other hand, when the shaft 1, the 90 disc 3 and the arm 5 are rotated in a direction opposite to that indicated by the arrows in Fig. 1, the arm 5 will travel toward the right hand, allowing a relative motion between the eccentric disc 3 and the annulus 95 7. Owing to the eccentricity of the disc 3 within the annulus 7 there will be a wedging action between these parts. This will firmly bind the disc 3, annulus 7 and gear 8 together, thereby forming a positively operating clutch which will cause all of the 100 said parts to rotate together in the same direction. Any device which it is desired to drive by means of the gear 8 will therefore be rotated. If, instead of the gear 8, a fixed 105 ring 10 is used, the driving shaft 1 will be permitted to rotate in the direction indicated by the arrow in Fig. 1, but will be stopped from rotating in the opposite direction, since the connection between the eccentric disc 3, the annulus 7 and the fixed member 10 will immediately become oper- 110

ated to form an effective brake in the nature of a ratchet.

The above description explains the general principle upon which our invention is based, and the parts so described may be applied to various devices in which the effects referred to are desired.

Referring now to Fig. 3, the parts therein indicated are so arranged as to constitute 10 a clutch for moving the driven part in either direction, but when not operative as a clutch the parts will be effectively locked in a stationary position, so that the driven member cannot be moved by the parts with 15 which it is connected.

Referring to Figs. 3 and 4, the numeral 12 indicates a suitable casing between the plates of which is carried a rotatable shaft 13, which rotatably carries on one end there- 20 of a driving member such as a gear 14. This driving member also carries a laterally projecting pin 15. The shaft 13 also carries a driven member, such as the gear 16, which is free to rotate thereon or may be 25 attached rigidly thereto if preferred. The driven member 16 has a laterally projecting circular portion 18 which is eccentric to the axis of the shaft 13. Surrounding the eccentric portion 18 of the driven member 16 30 is a fixed drum or annular flange 19, and between the flange 19 and eccentric projection 18 are located two curved wedges 20 and 21, which correspond on their inner and outer surface with the surfaces of the eccen- 35 tric projection 18 and the inner surface of the flange 19, respectively. The driven member or gear 16 carries a laterally projecting pin 22 adapted to project into the space between the driven member 16 and 40 the driving member 14, as clearly indicated in Fig. 3. A U-shaped spring 23 has its ends fixed, respectively, in the ends of the curved wedges 20 and 21, and tends to expand and keep said wedges separated so that 45 the same are forced with some slight pressure between the eccentric portion 18 of the driven member and the fixed flange 19.

The operation of the device above described will be explained as follows: When 50 the parts are in the position indicated in Fig. 2, any tendency of external force to move the gear or member 16 will be prevented, because the curved wedges 20 and 21 effectively clamp the eccentric member 55 18 in a fixed position, owing to the action of the spring 23 in forcing the wedges into their wedging position. On the other hand, however, should the driving member 14 be rotated counter-clockwise as in Fig. 2, the pin 60 15 will move toward the right, as indicated at 15' until it strikes the smaller end of the curved wedge 21. Thereafter said curved wedge will be moved with the motion of the pin 15 until its upper or larger end strikes 65 the pin 22. During this motion toward the

right the pin 15 has loosened the wedge so that its holding action is no longer effective against the flange 19, and as soon as its upper end strikes the pin 22 the motion of the driving member 14 and the driven member 16 will be the same, because the action of the eccentric portion of the driven member will be also in the direction of the arrow, and will not be opposed by the left hand curved wedge 20, which will simply follow 75 the motion of the eccentric portion 18 without any substantial retarding action.

The preferred modification indicated in Figs. 4, 5 and 6 operates in a similar manner to that shown in Figs. 2 and 3, but the 80 construction is slightly different. The form shown in Figs. 4 and 5, and when applied to a window raising and lowering device, as in Fig. 6, comprises a driving member or gear 14, a driven member or sprocket wheel 16 and an eccentric projection 18, all mounted on the shaft as described in connection with Figs. 2 and 3. The expansion spring 23 is also inserted between the ends of similarly curved wedges 20 and 21. However, the pin which projects from the driving member 14 is somewhat longer, as indicated at 24, and enters into a slot or groove 25 in the driven member 16.

The operation of this form of device is 95 as follows: When the parts are in the position indicated in Fig. 4, the driven member 16 will be held firmly in position by the action of the spring 23 in forcing the wedges 20 and 21 between the eccentric portion 18 of the driven member and the fixed flanges 19. However, when the member 14 is moved in the direction of the arrow in Fig. 4, the pin 24 will first strike the lower end of the wedge 21 and move it out of its wedging 100 position. Further movement of the pin 24 will cause it to strike the end of the slot 25 in the driven member 16 and thereafter the driving member and driven member will 105 rotate together, as described in connection with the form of the device in Figs. 2 and 3.

In applying this form of device to the window raising and lowering mechanism shown in Fig. 6, the driven member is a sprocket wheel 26 which is engaged by a sprocket chain 27, the lower end of which is connected directly with the glass or frame of the window. The opposite end of the sprocket chain 27 is connected with a counter balancing drum 28 which contains a 110 spiral spring, as is well known in the art. The driving member or gear 14 is adapted to engage a pinion 29 which is rotated by the usual handle or crank 30.

Having in mind the operation of the device as described in connection with Figs. 4 and 5, it will be seen that when the handle 30 is rotated toward the left, as in Fig. 6, the gear 14 will be rotated counter-clockwise, and when the pin 24 reaches the end 115 120 125 130

of the slot 25 the sprocket wheel 26 will also be rotated and the sprocket chain 27 operated to raise the window. A reverse motion of the handle allows the window to 5 descend or open, but when the handle 30 is not moved in either direction, the wedges 20 and 21 will lock the sprocket wheel 26 in position regardless of the motion of the automobile along the road, which would otherwise tend to displace the position of the 10 window and parts connected therewith.

Having thus described this form of our invention, we do not wish to be understood as being limited to the details of form and 15 the exact relation of the parts set forth, for various changes may be made by those skilled in the art without departing from the spirit and scope of our invention.

What we claim and desire to protect by 20 Letters Patent is:

1. An automatic clutch, comprising a rotary driving member, a member adapted to be rigidly connected therewith, an intermediate curved wedging member, said wedging member being adapted to become operative 25 when said driving member is moved in one direction, and means carried by said driving member for holding said wedging member out of operative positions when said driving member is rotated in the opposite direction.

2. An automatic clutch, comprising a rotary driving member, a member adapted to be rigidly connected therewith, intermediate segmental wedging members, means 35 for holding said wedging members in operative position, and means operated by said driving member for forcing one of said wedging members out of operative position when said driving member is rotated in either direction.

3. An automatic clutch, comprising a rotary driving member, a driven member adapted to be connected therewith, a fixed 45 braking member, wedging members between said fixed member and said driving member, means for holding said wedging members in operative positions, means extending between said driving member and said driven member and adapted to force one of said wedging members out of operative position 50 when rotated in either direction and to rotate said driven member.

4. An automatic clutch, comprising a rotary driving member, a driven member 55 adapted to be connected therewith, a fixed braking member, curved wedges between said fixed member and said driving member, resilient means for holding said wedges in operative positions, means operated by said driven member and adapted to force one of said wedges out of operative position when rotated in either direction and to rotate said driven member.

5. An automatic clutch, comprising a rotary driving member, a driven member 60 adapted to be connected therewith, a fixed braking member, curved wedges between said fixed member and said driving member, an expanding spring for holding said wedges in operative positions, means extending between said driving member and said driven member to form a driving connection therebetween and located to force 65 one of said wedges out of operative position when rotated in either direction by said driving member.

6. An automatic clutch, comprising a rotary driving member, an eccentric part carried thereby, a fixed braking member, segmented curved wedges between said part and said braking member, a spring for holding said wedges in operative positions, means extending between said driving member and said driven member to form a driving connection therebetween and located to force 70 one of said wedges out of operative position when rotated in either direction by said driving member.

7. An automatic clutch, comprising a rotary driving member, an eccentric part carried thereby, a fixed braking part, segmental curved wedges between said eccentric and braking parts, a spring for holding said wedges in operative positions, a pin carried 75 by said driving member and adapted to engage said wedges to force either one thereof out of operative position when rotated in either direction, said driven member being provided with a stop portion against which said pin is adapted to bear to rotate said driven member.

Signed this 1st day of November, 1924.

HARRY P. STEVENS.
